UNITED STATES PATENT OFFICE.

CHARLES H. STARIN, OF BROOKLYN, NEW YORK, ASSIGNOR TO HIMSELF AND GEORGE W. CHAUNCEY AND JOHN C. HARVEY, BOTH OF SAME PLACE.

ASH-SIFTER.

SPECIFICATION forming part of Letters Patent No. 242,071, dated May 24, 1881.

Application filed April 1, 1881. (No model.)

To all whom it may concern:

Be it known that I, CHARLES H. STARIN, of Brooklyn, in the county of Kings and State of New York, have invented a new and Improved Ash-Sifter, of which the following is a full, clear, and exact description.

My invention consists in a box with an inclined top provided at the lower end with a hinged door, and at the upper end with a chute 10 closed by a balanced gate, through which chute the ashes are dropped upon an inclined sieve or grating, down which they slide, the ashes dropping into a box below the sieve and the cinders accumulating in the lower end of the 15 box, from where they can be removed through the above-mentioned hinged door.

In the accompanying drawings, Figure 1 is a longitudinal sectional elevation of my improved ash-sifter. Fig. 2 is a plan view of the 20 same, showing parts broken out to show the grating.

The box A is provided with an inclined top, B, provided at the lower end with a hinged door, C, and at the upper end with a chute, D, 25 which is closed by a downward-swinging gate, E, which rests against a shoulder, F, of the inner sides of the chute. A bent wire, G, is attached to the inner end of this gate E, and a weight, H, is attached to the outer end of this 30 wire G, and keeps the gate closed; or the gate may be balanced in some other suitable manner.

A transverse partition, J, rests on the floor K of the box a short distance in front of the 35 middle of the same, and a grating, L, made of parallel bars M, or a sieve of wire-netting, rests on the top of the partition J and against the rear wall, N, of the box, in such a manner that it will be parallel with the top B, and will be 40 a short distance from the same.

A box, O, is passed into the box A through an opening, P, in the rear wall, N, of the same, so that it will be below the grating L, the rear end of this box fitting closely in the opening P.

The box A is provided with bail R, for transporting it.

The operation is as follows: The ashes are passed into the chute D, and their weight depresses the gate E, permitting them to drop upon the grating L, down which they slide. 50 The ashes drop through the interstices between the bars M into the box O, and the cinders slide down the grating and accumulate in the lower part of the box, and can be removed through the door C. The ash-box O can be 55 drawn out of the box to remove the ashes. As the gate E is closed automatically by the weight H as soon as ashes have passed, the dust will all be confined in the box A.

Having thus described my invention, what 60 I claim as new, and desire to secure by Letters Patent, is—

1. In an ash-sifter, the combination of a box having hinged door C at the lower end of incline B, and the chute D at the upper end, the 65 balanced gate E, the grating L, supported on transverse partition J, and the sliding box or drawer O, substantially as shown and described.

2. In an ash-sifter, the combination, with the chute D, through which the ashes and cinders 70 are passed, of the hinged gate E, the bent wire G, and the weight H, substantially as herein shown and described, and for the purpose set forth.

CHARLES H. STARIN.
